CLAIM

The ornamental design for a fascia gun, as shown and described.

DESCRIPTION

FIG. 1 is a bottom, front, and right-side perspective view of the fascia gun showing my new design;

FIG. 2 is a top, rear, and left-side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the fascia gun that form no part of the claimed design.

1 Claim, 8 Drawing Sheets
